UNITED STATES PATENT OFFICE.

ELIAS A. CLEAVELAND, OF BELVIDERE, ILLINOIS.

BED-BOTTOM.

No. 836,092.

Specification of Letters Patent.

Patented Nov. 20, 1906.

Application filed January 11, 1905. Serial No. 240,602.

To all whom it may concern:

Be it known that I, ELIAS A. CLEAVELAND, a citizen of the United States, residing at Belvidere, in the county of Boone and State of Illinois, have invented certain new and useful Improvements in Bed-Bottoms, of which the following is a specification.

The object of this invention is to construct a bed-bottom in which the end bars are connected by tubular side bars let into the end bars, thereby producing a strong and rigid frame.

The further object of this invention is to provide means located beneath the wire fabric of the bed which impart additional strength to the fabric.

In the accompanying drawings, Figure 1 is an under face representation of a bed-bottom containing my improvements. Fig. 2 is a lengthwise section on dotted line *a a*, Fig. 1. Fig. 3 is a transverse section on dotted line *b b*, Fig. 1. Fig. 4 is a perspective view of a section of one of the end bars. Fig. 5 is a perspective view of a section of one of the tubular side bars.

The end bars 1 and 2 are formed of wood, and near the ends of each are formed semi-circular cavities 3. Tubular side bars 4 and 5 have their ends closed, and each end has a perforation 6. The end sections of these tubular side bars are located in the semicircular cavities 3 in the wooden end bars 1 and 2 and are secured in position by the bolts 7.

The side bars being tubular, they will impart the necessary strength to the structure, and their ends being let into the wooden end bars will hold the frame from racking. A single bolt in each end of the tubular side bars will serve to connect them with the end bars.

The wire fabric 8 is connected to the end bars of the frame in the usual manner. Beneath the wire fabric and supported by the end bars of the frame are located a series of additional supports for the fabric, and as all the supports are the same in construction a description of one will answer. In the end bar 2 of the frame is turned a screw-eye 9, and in the end bar 1 is turned a screw-eye 10. A screw-hook 11 has a connection with the screw-eye 9, and a screw-hook 12 has a connection with the screw-eye 10. An equalizing-bar 13 has a connection with the screw-hook 11, and a nut 14 holds it in engagement therewith. The ends of this equalizing-bar

are in hook form. A yielding equalizing-bar is formed with wire having a center coil 15 and its branches extending from the coil having hooked ends. Within the coil of the yielding equalizing-bar is located a stud 16, 6c provided with a transverse opening 17 and a head 18 on its end opposite to the end having the opening. The screw-hook 12 is located in the transverse opening 17, and a nut 19 is placed on the screw-hook. Two stay-wires 65 20, connected to helical springs 21, have their ends connected to the equalizing-bar and to the yielding equalizing-bar.

By means of the helical springs and the spring action of the yielding equalizing-bar 70 the wire fabric is supported in a flexible manner, and by means of the nuts 14 and 19 the tension of the helical springs and of the yielding equalizing-bar can be adjusted to suit the weight of the person occupying the bed. 75

By locating a series of these supports beneath the wire fabric of the bed and each support independently adjustable should two persons of different weights occupy the bed 80 each side can be adjusted independent of the other side, so that both persons will lie on the same level.

The construction of the frame of the bed-bottom herein shown and described is not claimed herein, but forms the subject-matter 85 of a divisional application, filed September 27, 1906, Serial No. 336,428.

I claim as my invention—

1. A bed-bottom composed of end and side bars, an equalizing-bar supported by a screw hook and eye connection with one of the end bars, and having its ends in hook form, the screw-hook passing through the equalizing-bar and having a nut on its end, and helical springs having a connection with the equalizing-bar and with the other end bar. 95

2. A bed-bottom composed of end and side bars, a yielding equalizing-bar composed of wires having a center coil and two extending branches, connections between the branches and one of the end bars, a headed stud located in the coil, a screw-hook having a connection with the stud, a nut on the screw-hook, and a screw-eye connection with the other end bar with which the screw-hook engages. 105

3. The combination of a bed-spring, an equalizing-bar, two wires connected to the equalizing-bar, a rod for each equalizing-bar extending through the center portion of the bar, an adjustable nut on one end of said rod, 110

a connection between the rod and one end bar of the bed-spring, and the wires having a connection with the other end bar.

4. In a bed-spring, the combination with 5 a frame, and a sheet of flexible material stretched between the frame-bars, of two wires connected with one frame-bar and arranged in sets, equalizing-bars having their ends connected with the respective wires of 10 a corresponding set, a rod for each equaliz-

ing-bar extending through the center portion of the bar, an adjusting-nut on the inner projecting end of each rod, and a connection between the other projecting end of each rod and one of the frame-bars.

ELIAS A. CLEAVELAND.
